G. E. SWARTZ.
ADJUSTABLE DRILL JIG.
APPLICATION FILED AUG. 6, 1917.

Patented Aug. 12, 1919.

Attorneys

UNITED STATES PATENT OFFICE.

GUY E. SWARTZ, OF DETROIT, MICHIGAN.

ADJUSTABLE DRILL-JIG.

1,312,767.

Specification of Letters Patent. Patented Aug. 12, 1919.

Application filed August 6, 1917. Serial No. 184,720.

To all whom it may concern:

Be it known that I, GUY E. SWARTZ, a citizen of the United States of America, residing at Detroit, in the county of Wayne 5 and State of Michigan, have invented certain new and useful Improvements in Adjustable Drill-Jigs, of which the following is a specification, reference being had therein to the accompanying drawings.

10 This invention relates to adjustable jigs for holding work to be operated upon and refers more particularly to a new and improved adjustable and universal jig of the character above referred to.

15 Among the objects of the invention are to provide an improved means for quickly and accurately clamping and releasing the work; to provide a construction which can be adjusted to different heights to take care of

20 different sizes of members to be held; to provide a construction having interchangeable adapters for holding work of various kinds, these adapters being preferably adjustable for height with the movable member of the

25 jig; to provide a construction wherein the work is clamped by spring actions, also in combination with a lever cam or other suitable member for moving the adjustable member back against the tension of the

30 spring when it is desired to release the work.

The invention also resides in such other features of construction and arrangements and combinations of parts as will more fully hereinafter appear.

35 In the drawings:

Figure 1 is an end elevation, partly in section of a device embodying my invention;

Fig. 2 is a fragmentary elevational view of the construction shown in Fig. 1;

40 Fig. 3 is a fragmentary top plan view;

Fig. 4 is a top plan view of the releasing lever;

Fig. 5 is a fragmentary horizontal section on the line 5—5 of Fig. 1.

45 Describing in detail the particular construction shown in the drawings, A designates the bed plate or stationary member of the jig which is provided with a seat B formed to receive an adapter C which can

50 be of any desired form to suit the work. The adapter is removably held in the seat B by a locking bolt or set-screw D. Extending upward from the bed plate A is a post E upon which there is slidably mounted the

55 movable member F of the jig. This movable or clamping member F is also provided with

a seat G for receiving interchangeably a work-holding adapter H. The work holding adapter H is in turn provided with a slip bushing H' which can be easily interchanged to correspond to the size of hole desired; also the base B is provided with a pin or post B' serving as a stop to keep the work from rotating with the drill.

As shown in Fig. 1 the work, such as the bracket I, is clamped between the adapters C and H, the clamping member F being forced toward the stationary member or bed plate A by means of any suitable spring arrangement, as for instance, by the spiral coil 65 spring J. The latter is sleeved upon the post E and has its upper end bearing against an adjustable locking nut J'. This locking nut is turned down on the threaded end E' of the post E a sufficient distance to compress 70 the spring and thus cause the latter to normally spring-press the clamping member F toward the bed plate. In addition to the post E the clamping member F is guided by a post or guide bar K having flat sides K' 75 engaged by a recessed portion K² on the clamping member F.

After moving the clamping member back from the work and against the tension of the spring J, I preferably employ a lever L 85 pivotally connected at L' to the clamping member F and pivotally connected at L² to lifting rods L² and L³ which extend through the clamping member F and by a toggle link M to the base A at M'. Thus when the 90

operator desires to lift the clamping member F to release the work he pushes down upon the lever L which, operating on the link M as a fulcrum, forces the clamping member F upward, withdrawing the adapter or 95

holder H so as to release the work. To compensate for adjustments of the nut J' to take care of clamping articles of different sizes, the lifting rods L² and L³ have their upper ends threaded to adjustably receive the locking nuts N and N'.

For holding the upper adapted H in the seat G, I employ a set-screw O, similar to the set-screw D for the lower adapter. Thus both the stationary and movable members are provided with interchangeable adapters and the normal position of the upper clamping member can be adjusted to various spaced relations with reference to the base A.

However, while I have shown and described a jig having a single post, the invention in certain of its aspects is not limited to this particular type 100 105 110

but could be used as stationary, revolving or multiple types, particularly adapted for continuous loading. Various changes in the details of construction covering the above types 5 can also be made within the scope of the claims.

What I claim as my invention is:—

1. A combined adjustable and universal jig having a stationary member, a coacting movable clamping member, a post projecting from the stationary member and forming a guide for the clamping member, a spring coiled upon said post bearing at one end upon the clamping member to press the same 10 toward the stationary member, an adjusting nut engaging a threaded portion of the post forming an abutment for the other end of said spring, and lever mechanism for adjusting the movable clamping member away 15 from the work against the tension of the spring.
2. A jig comprising a stationary member, a coacting movable clamping member, a post on said stationary member carrying a spring

pressing said movable member toward the 25 stationary member for clamping the work therebetween, an abutment for the other end of said spring adjustable upon said post, and lever mechanism for adjusting the movable member away from the work against 30 the tension of said spring.

3. A combined adjustable and universal jig having a stationary member, a coacting movable clamping member, a coil spring acting at one end on said clamping member to 35 urge the same toward the stationary member, an abutment for the other end of said spring adjustable as regards its distance from the stationary member, an actuating member for the movable clamping member, 40 and a connection between the actuating member and movable clamping member adjustable as regards its connection to one of said members to permit a variation of the working position of the movable clamping 45 member.

In testimony whereof I affix my signature.
GUY E. SWARTZ.
